UNITED STATES PATENT OFFICE

HARTWELL L. EDRIDGE, OF MINNEAPOLIS, MINNESOTA

AIR CLEANER FOR INTERNAL COMBUSTION ENGINES

Application filed January 23, 1930. Serial No. 422,725.

This invention relates to an improved air cleaner for use in connection with internal combustion engine carburetors and, generally stated, the invention consists of the novel devices and combination of devices hereinafter described and defined in the claims. An object of this invention is the provision of a very efficient and relatively inexpensive air cleaner for internal combustion engines that will not retard the velocity of air entering the carburetor intake of the engine. This and other objects will be brought out clearly in the specification, claims and drawings.

In the accompanying drawings, which illustrate the invention, like characters indicate like parts throughout the several views.

Referring to the drawings:

Fig. 1 is a diagrammatic view of an internal combustion engine and illustrating my air cleaner in connection therewith;

Fig. 2 is a front end elevation of the air cleaner; and

Fig. 3 is an axial section taken on the line 3-3 of Fig. 2, some parts being shown in full and some parts being broken away.

The motor block of the internal combustion engine, diagrammatically illustrated in Fig. 1, is indicated as an entirety by the numeral 4, the radiator of its cooling system by the numeral 5, the cooling fan by the numeral 6, the intake manifold by the numeral 7, and the carburetor by the numeral 8, which carburetor is provided with a forwardly opening air intake neck 9.

The casing of the air cleaner, indicated as an entirety by the numeral 10, is annular in cross-section and is open at its front end and is provided at its rear end with a rearwardly extended co-axially aligned sleeve 11. Axially centered in the front portion of the casing 10 with its apex pointing forward and substantially aligned with the open front end of the casing is a conical baffle 12, the base of which baffle is of less diameter than the surrounding portion of the casing. The space between the conical baffle 12 and the surrounding casing 10 affords an annular air intake 13 of quite great area. In this annular air intake extending between the conical baffle 12 and the casing 10 is an annular series

of circumferentially spaced deflecting blades for causing incoming air to take up a whirling motion.

Projecting from the casing through and beyond the sleeve 11 is a clean air outlet tube 15. The portion of this outlet tube 15 that is within the sleeve 11 has an outside diameter of considerably less than the inside diameter of the surrounding sleeve 11 and is centered therein so as to afford an annular dust discharge passage 16 therebetween that is closed near the end of the sleeve 11 by a spacing and retaining collar 17. The sleeve 11 of the casing 10 and the clean air outlet tube 15 are each soldered, welded or otherwise secured to the collar 17 and are thereby held together as a single unit. The inner portion of the outlet tube 15 inward of the sleeve 11 is a flare toward its open inner end, which inner end is of approximately the same but of not greater diameter than the base of the conical deflector 12. The open inner end of the clean air outlet tube 15 is directly behind but spaced from the base of the conical deflector 12 to afford a free passage for clean air from the annular air inlet 13 to the clean air outlet tube 15. Depending from the under rear portion of the sleeve-like casing extension 11 and opening into the annular dust discharge passage 16 is a dust discharge spout 18. This discharge spout 18 opens into a porous dust receptacle 19 comprising a fabric bag or sack 20 reinforced at its inside to keep the same from collapsing by means of a wire netting or screen 21.

The open upper end of the fabric sack is telescoped over the open end of the discharge spout 18 and is detachably retained thereon by means of a clamping band or the like 22.

When the air cleaner is in working position, the projected rear end portion of its clean air outlet tube 15 is telescoped into the forwardly opening end of the carburetor intake neck 9, as shown in Fig. 3, so that the end of the carburetor neck 9 strikes and is stopped by the collar 17. The cleaner is normally removably held in place by means of a set-screw or the like 23 that has screw-threaded engagement with the carburetor neck 9.

It is important to note that the annular

air intake of the air cleaner opens forwardly and is directly subject to the air passed through the radiator caused by forward movement of the vehicle and the action of the 5 fan 6, directly in the blast of which fan said annular air intake 13 is located. It is also important to note that the area of the annular air intake 13 is greater than the combined area of the clean air outlet tube 15 and the 10 annular dust outlet 16. It will now be apparent that when the cleaner is in use, air will enter the casing 10 through the annular opening 13 at relatively high velocity due to the rapid rearward movement of air caused by 15 the movement of the vehicle and the action of the fan and in sufficient volume due to the size or area of the annular air intake 13 to supply the carburetor intake neck 9 through the clean air outlet tube 15, and maintain a 20 pressure within the casing that will at all times cause dust-laden air to be moved rapidly through the annular dust outlet 16 and dust outlet spout 18 to the dust collecting bag or sack 19. The dust will be retained in the 25 collector 19 and the air will be blown rapidly therethrough to the atmosphere.

Air entering the annular air intake 13 will strike the annular series of circumferentially spaced deflecting blades 14 and be 30 caused to take up a rapidly whirling motion and due to this whirling motion and aided by the conical deflector 12, dust or heavier than air particles carried by the incoming air will be thrown outward by centrifugal 35 force to the sides of the casing 10 and said dust will follow the sides of said casing to the annular air dust outlet 16 in spiral rearward movement and will be passed from said dust outlet 16 through the spout 18 to the 40 dust collector 19. The air, near the inner portions of the annular air inlet 13, close to the conical deflector 12, will be clean or in other words will have had the heavier than air particles separated therefrom by centrifugal 45 action and this air will pass into the flaring inner end of the clean air outlet tube 15 and be passed through the carburetor to the intake manifold 7 and thence to the engine. It is well-known that the vacuum 50 created in air intakes of internal combustion engines is great especially at high speeds and that it is detrimental both to the maximum speed and efficiency of the engine to place anything in the air intake that will cause 55 additional resistance and tend to raise this vacuum. With my air cleaner, however, air is always supplied to the interior of the cleaner casing 10 in sufficient volume to at all times maintain at least atmospheric pressure 60 within the casing and usually this pressure will be above atmospheric pressure and will, therefore, increase the efficiency of the engine especially at high speed by delivering the clean air to the carburetor intake under pressure and thereby decreasing the resistance 65

and lowering the partial vacuum in said engine air intake.

By flaring the inner end portion of the clean air outlet tube 16 so that its extreme open end is approximately the same diameter as the base of the conical deflector 12, incoming air close to the conical deflector 12 is only caused to change its course of travel to a relatively small degree in order to enter the open end of the clean air outlet tube 15 and in this manner the least possible resistance to the clean air is produced. Dust once thrown to the side of the casing by centrifugal force caused by the deflecting blades 14 is very rapidly carried away by the rapid movement 75 of air which is present under operating conditions through the annular dust outlet 16, spout 18 and into and through the dust receptacle 19.

The pores in the dust receptacle 19 are fine 85 enough so that the dust will not be passed therethrough but will permit, due to the relatively large area of said receptacle, a very rapid movement of air therethrough.

What I claim is:

1. An air cleaner comprising an annular casing that is open at its front end and having an axial opening at its rear end portion, a conical baffle concentrically located within the front portion of said casing with its apex 95 pointing forward and its base being of less diameter than the surrounding portion of said casing to afford an annular air inlet between said baffle and said casing, an annular series of circumferentially spaced deflecting 100 blades in said annular air inlet and extending between said conical baffle and said casing, a clean air outlet tube extended axially from said casing through said opening in the back thereof and its open inner end terminating close to the back of the base of said conical baffle, and said clean air outlet tube being of less diameter than the opening in the back of the casing at its point adjacent said opening to afford an annular dust discharge passage surrounding said tube, and a porous dust collector arranged to receive all of the dust laden air passed through the annular dust discharge passage and retain the dust and permit free discharge of air.

2. An air cleaner comprising an annular casing provided at one end with an annular air inlet and at its opposite end with an axial opening, deflecting means in said annular inlet for causing heavier than air particles carried by incoming air to be thrown outwardly of said casing, said casing being tapered from its intermediate portion toward said axial opening, a clean air outlet tube extended axially through said opening for receiving clean air from the central portion of the casing and being spaced from the sides of said opening to afford an annular dust outlet surrounding said tube through which 110 annular dust outlet dust laden air following 115

the sides of said casing will pass, and a porous dust collecting bag arranged to receive the dust laden air passed through the annular dust outlet and to retain the dust and 5 permit air to be exhausted therethrough.

3. An air cleaner comprising an annular casing that is open at its front end and being contracted at its rear end and terminating in a rearwardly extended coaxial sleeve, a conical baffle concentrically located within the front portion of the casing with its apex pointing forward and its base being of less diameter than the surrounding portion of 10 said casing to afford an annular air inlet between said baffle and said casing, an annular series of circumferentially spaced deflecting blades in said annular air inlet and extending between said conical baffle and said casing, and a clean air outlet tube extended 15 axially from said casing through said sleeve at the rear of the casing, the portion of said outlet tube within said sleeve being spaced from said sleeve to afford an annular dust discharge passage between said tube and said 20 sleeve and the portion of said sleeve within said casing being expanded toward its open end and terminating in close relation to the base of the conical baffle in an open end of 25 substantially the same diameter as the base 30 of said conical baffle.

In testimony whereof I affix my signature.
HARTWELL L. ED RIDGE.
